corporation of New York

Application March 1, 1946, Serial No. 651,279

23 Claims. (Cl. 164—54)

1

My present invention relates to paper cutting machines of the guillotine type and more particularly to hydraulic operating means for the clamping mechanism used in such machines.

In paper cutting machines wherein the knife is caused to descend downwardly and move at the same time laterally with respect to a paper pile on the work table, it has long been found necessary to provide clamping mechanism which contacts the paper pile just before the knife blade reaches it, squeezes the air out of the paper pile just behind the knife blade and holds the paper pile steady while the knife blade is going through. Since relatively great force, of the order of tons, must be exerted by the clamp, various mechanical as well as hydraulic force multiplying means have previously been suggested and in some cases used to clamp the paper.

Attempts have been made to drive the clamp through its entire stroke by hydraulic pressure derived from a pump. Owing, however, to the rapid action of the knife of a paper cutting machine hydraulic pressure thus derived driving the clamp through its entire stroke is both expensive in initial cost of equipment as well as in operation. In order to obtain force multiplication the stroke of the operating members in the case of such prior hydraulic drives for the operation of the clamp must be over a length or angle many times that of the stroke of the clamp.

In other prior devices, hydraulic means have been utilized simply for power transmission to the clamp without force multiplication; the full pressure must then be developed in the driving mechanism.

A primary object of my invention is the arrangement of clamp operating means in such manner that force multiplying hydraulic driving means are used over a relatively minute portion of the stroke; that is the force multiplying hydraulic means comes into operation only after the clamp has contacted the paper pile. The force multiplying hydraulic means is then operative to force the clamp tightly down on the paper pile.

Another and corollary object of my invention is the provision of combined driving means for the clamp of a paper cutter wherein the clamp is moved down mechanically into contact with the upper surface of the paper pile on the work table and after such contact has been made the force multiplying hydraulic means is brought into operation to force the clamp with great pressure against the paper pile. Since the hydraulically operated portion of the stroke is thus relatively minute, large forces may be developed on the

2

clamp even though the applied force is considerably smaller.

The foregoing and many other objects of my invention will become apparent in the following description and drawings in which:

Figure 1 is a schematic view showing my novel clamp in a raised position.

Figure 2 is a schematic view showing my novel clamp brought down into contact with the paper prior to the application of hydraulic pressure thereto.

Figure 3 shows the clamp of Figures 1 and 2 with force multiplying hydraulic pressure applied to the clamp.

Figure 4 is a schematic side view of the clamp of Figures 1 to 3 taken from line 4—4 of Figure 1.

Figure 5 is a corresponding view taken from line 5—5 of Figure 2.

Figure 6 is a view of a slightly modified form of clamp operating device showing the raised position of the clamp.

Figure 7 is a schematic view showing the clamp lowered into contact with the paper stack.

Figure 8 is a schematic view showing the application of force multiplying hydraulic pressure to the clamp of Figures 6 and 7.

Referring now to Figures 1, 2 and 3, the clamp 10 comprises a transverse bar or casting having the clamping surface 11 and is free to reciprocate vertically in guides schematically indicated at 12 and 13 in the frame of the paper cutter. The clamp 10 operates above the work table 15 of the paper cutter on which stacks of paper may be placed to be cut. The paper cutter also includes a knife blade not shown which is mounted just in front of the clamp 10 and is so arranged that it will come into contact with the paper immediately after the clamp has engaged the paper and compressed it. The knife blade and the knife operating mechanism is not shown since it constitutes no part of the present invention.

However, it is understood that when a paper stack is placed on the work table 15 and the paper cutter is tripped into operation, the surface 11 of clamp 10 is brought down onto the paper stack on work table 15 and compresses it just before the knife edge enters the paper stack and the clamp is arranged to rise just after the knife edge on its withdrawal from the paper stack leaves the stack.

The clamp 10 is provided with a pair of opposite lateral extensions 17, 18 having the pins 19, 20 to which are attached the pull bars 21, 22.

The lower end of pull bar 22 is connected to the pin 23 at the upper end of bell crank lever 24.

The lower end of pull bar 21 is connected to the pin 25 at the upper end of bell crank lever 26.

Bell crank levers 24 and 26 are pivoted on the studs 30, 31. The lower end of bell crank lever 24 is connected at the pin 33 to the link 34, the opposite end of which is connected by pin 35 to the lug 36 of hydraulic piston 37.

The lower end of bell crank lever 26 is similarly connected by pin 40 to link 41, the opposite end of which is connected by pin 42 to the lug 43 of hydraulic piston 44.

Pin 33 on the lower end of bell crank lever 24 is also connected to the vertical link 50 which is a single rigid member from the pin 33 to the lower pin 52. The single link 50 is connected, approximately midway between pins 33 and 52, by the pin 53 to the link 54, the opposite end of which is connected by pin 55 to the driving crank 56.

The lower end of link 50 is connected by pin 52 to link 59, the opposite end of which is connected by pin 60 to the piston rod 61, which carries the piston 62 rigidly secured thereto. Piston rod 61 extends through piston 62 to the opposite side forming extension 61a.

Valve 65 is slidably mounted on extension 61a of the piston rod 61 and is biased toward the left on this extension by the compression spring 67 captured between surface 68 of valve 65 and collar 69 secured at the right hand end of extension 61a. Consequently, valve 65 is biased toward the left but after it has reached its limit of movement to the left, as hereinafter described, the piston rod 61, piston 62 and extension 61a of piston rod 61 may slide with respect to the valve 65.

Pistons 37 and 44 operate horizontally in the horizontal cylinder 70. Fluid intake duct 71 and cylinder 70 communicates at its lower end with the duct 72 connected with the fluid reservoir 73.

Valve 65 in the position shown in Figure 1 permits the free flow of fluid from reservoir 73 and duct 72 up through the intake duct 71 into the cylinder 70. Valve 65 is arranged so that when it is moved from the position shown in Figure 1 to the position shown in Figure 2 it blocks the lower portion of fluid intake duct 71 and thus seals the fluid intake 71 of the cylinder 70 from the reservoir 73. For this purpose, as the rod 61 and piston 62 moves to the left drawing piston extension 61a and collar 69 along, the valve 65 also moves to the left across the duct 71 until the end 75 of valve 65 fits against the shoulder 76 at the left side of duct 71 thus sealing and blocking off the lower portion of duct 71.

As the piston 62 moves still further to the left to the position shown in Figure 3, the piston rod 61 and its extension 61a slide with respect to the valve 65 which remains stationary thus compressing the spring 67.

Piston 62 operates in the lower cylinder 80 which communicates with the duct 81, duct 81 communicates through the check valve 82 with the duct 83 which communicates with duct 71 at a point above the blocking valve 65.

Check valve 82 is arranged so that it may open upwardly and is biased closed against the valve 85 by compression spring 86.

An additional check valve 90 is provided at the lower end of duct 81 closing the passage between duct 81 and duct 72. This valve is biased by its own weight downwardly against the seat 91 and is arranged that it may only open in an upward direction.

A discharge valve 95 is also provided being biased upwardly closed against its seat 96 by the compression spring 97 around the valve stem 98.

between the under-surface of valve 95 and the adjusting knob 99.

In operation, a stack of paper 100 is placed on the work table 15 and the paper cutting mechanism is tripped into operation. The crank 56 is rotated counterclockwise by the drive mechanism thus forcing the link 54 to the left. Link 54 forces the pivot 53 and hence link 50 to the left counterclockwise around the pivot 52, which is held stationary by means of abutment 101 on the frame of the machine, against which the collar 69 of extension 61a of piston rod 61 rests. Counterclockwise rotation of link 50 forces pin 33 to the left causing the bell crank lever 24 to rotate in a clockwise direction.

With the duct 71 completely open and connecting reservoir 73 and duct 72 with the cylinder 70, the pistons 37 and 44 may readily follow the rotation of the bell crank levers 24 and 26. Rotation of bell crank lever 24 in a clockwise direction results in pulling down the pull bar 22 which thus pulls down the clamp 10.

Pull bar 21 accordingly moves down with clamp 10 and causes the bell crank lever 26 to rotate in a counterclockwise direction also pulling out the piston 44 to the right. This downward mechanical movement of the clamp 10 continues until the surface 11 of clamp 10 contacts the top of paper stack 100.

Pivot 33 now becomes stationary and cannot move since it is mechanically tied to the paper clamp, the movement of which is now blocked by the upper surface of paper stack 100.

Further rotation of crank 56 in a counterclockwise direction now, through link 54 and pin 53, forces the lower end 52 of link 50 to rotate in a clockwise direction and forces the entire link 50 to rotate about the pivot 33.

This now pulls on link 59 and piston rod 61 pulling the piston 62 to the left. As the piston rod 61 and piston 62 are pulled to the left the valve 65 moves from the non-blocking position of Figure 1 to the position of Figure 2 where it blocks the communication from reservoir 73 and duct 72 through duct 71 to cylinder 70. Cylinder 70 is thus blocked off from reservoir 73.

The further movement of crank 56 in a counterclockwise direction now pulls the piston 62 further to the left as shown in Figure 3 forcing the fluid from the lower cylinder 80 up through the duct 81 lifting the check valve 82 and forcing the fluid through duct 83 and the upper portion of duct 71 into cylinder 70.

In the position of Figure 2, it will be seen that cylinder 80, duct 81, duct 83, the upper portion of duct 71 and cylinder 70 are now a closed system. Consequently, any movement of piston 62 to the left in the lower cylinder 80 will cause a hydraulic transmission of power through the closed system to the pistons 37 and 44. The power transmission will be a force multiplying transmission since piston 62 and lower cylinder 80 are of much smaller diameter than pistons 37 and 44 in upper cylinder 70. Consequently, the movement of piston 62 to the left after the position of Figure 2 has been reached and to the position of Figure 3 will result in forcing the pistons 37 and 44 outwardly with hydraulically multiplied force. This will cause simultaneous additional clockwise rotation of bell crank lever 24 and counterclockwise rotation of bell crank lever 26 pulling the pull bars 22 and 21 down at hydraulically multiplied force and thereby pulling the clamp 10 down upon the top of stack 100 with hydraulically multiplied force.

Valve 95 is provided as a discharge, pressure

regulating and safety valve; in the event that the piston 62 exerts too great a force on the pistons 37 and 44 of cylinder 70, it will be depressed and opened by this additional force to permit discharge of the excess liquid from cylinder 70 through duct 103 to reservoir 73.

This is necessary because the piston 62 is so arranged that it will be forced to travel to the left to a much greater extent with a high stack than with a lower stack in order to permit the crank 56 to make a full revolution.

After the high stack is contacted and the hydraulic mechanism is thus brought into operation, the paper can be compressed only to a limited extent and further complete travel of piston 62 to the left will result in breaking some portion of the mechanism. Consequently, discharge valve 95 is adjusted by the hand knob 99 so that it will bleed off excess liquid under pressure after full compression of the paper stack has been obtained, thus permitting piston 62 to make its full movement to the left.

With a very low stack piston 62 will be brought into operation relatively very late in the first 180° of rotation of the crank 56 and discharge valve 95 may not be forced to operate.

However, my novel device thus provides a method by which very high pressures are automatically obtained in a high paper stack for which such high pressures are required and relatively lower pressures may be obtained for a low paper stack which does not require high pressures.

The device is so arranged as shown that the clamp is brought down rapidly mechanically and after it has contacted the paper stack, the hydraulic mechanism is brought into operation to provide adequate clamping pressure.

After the apparatus has reached the position of Figure 3 and the knife has gone through the stack, the continued counterclockwise movement of crank 56 through the remaining 180° of said movement first causes a counterclockwise rotation of link 59 around pivot 33 moving link 59 and piston rod 61 to the right. When piston 62 engages the surface 75 of valve 65 it also forces the valve 65 to the right thus opening the duct 71 and establishing communication between the reservoir 73 and cylinder 70 to equalize the pressure of cylinder 70 with the atmospheric pressure of reservoir 73. At the same time, and in order to permit piston 62 to move readily to the right, the check valve 90 is so arranged that on such return movement of piston 62 to the right it is raised and fluid may flow from reservoir 73 through duct 72 up into duct 81 and lower cylinder 80 to permit equalization of pressure.

After the collar 69 on extension 61a of piston rod 61 has struck abutment 101 and further movement of piston 62 and the pivot 52 to the right is limited, then further rotation of crank 56 counterclockwise through the remainder of the return cycle will cause the link 50 to pivot clockwise around the pivot 52 driving the pivot 33 to the right and causing counterclockwise rotation of bell crank lever 24 thereby forcing up link 22 and pushing up the clamp 10.

Clamp 10 may, of course, be counter-balanced in any suitable well-known manner by appropriate springs so that the upward movement thereof is substantially aided by the springs.

Since during the mechanical movement downwardly of the clamp 10 the downward force on clamp 10 is exerted only on extension 18 thereof, there is a possibility that the clamp 10 may cant to the left. Also since the paper stacks will rare-

ly occupy the full width of the machine and are usually placed against the left hand guide, this introduces a further possibility of canting.

For this reason in order to prevent canting of the clamp, a horizontal shaft 110 (see also Figures 4 and 5) is arranged in the rear of the clamp 10 journaled in appropriate bearings 111, 111 supported in any suitable manner by the frame of the entire mechanism.

10 Gear segments 112, 112 are attached to the opposite ends of shaft 110 and mesh with the racks 113, 113 on the back of the clamp. The torsional stiffness of shaft 110 will, therefore, prevent canting or cocking of the clamp 10 owing to the fact that force is exerted directly during mechanical movement on only one side of the clamp or owing to the placing of a very narrow pile against one side of the work table.

This latter consideration that a narrow pile 20 may be placed against one side of the work table is of course the primary one as far as canting or cocking of the clamp is concerned since maximum force is exerted on the clamp 10 only by the hydraulic pistons 37 and 44 which operate 25 simultaneously on both sides of the clamp.

The reservoir 73 is provided with an appropriate opening 120 through which additional fluid may be introduced into the system. The level of fluid in the reservoir 73 should always be just 30 above the upper level of cylinder 70.

It will also be noted that in the system just shown in Figures 1, 2 and 3, the fluid is subject to pressure only in cylinders 80 and 70 and in ducts 81 and 82 and a portion of duct 71 between them.

35 The fluid in reservoir 73 and ducts 72 and 103 is never under pressure so that no special sealing means is required for opening 120 other than any well known means for excluding dust and 40 foreign matter and the opening 120 may readily be opened and inspected to determine that a proper fluid level is maintained.

By the means herein shown, therefore, I provide a simple, rapidly operated mechanical means

45 for lowering the clamp 10 quickly into engagement with the upper surface of the paper stack 100. As soon as this engagement is reached and the movement of the clamp 10 further downwardly is blocked by the paper stack then the

50 hydraulic mechanism is brought into operation to cause the clamp to squeeze the paper stack tight under force multiplying hydraulic pressure. Consequently, where the clamp is provided with a 6" working stroke and where a 3" pile of paper

55 is placed on the work table, the clamp is moved downwardly 3" mechanically to contact the upper surface of the paper pile and is then moved hydraulically the remaining fraction of an inch necessary to compress the paper pile just

60 prior to the movement of the knife blade thereto.

Thus since the hydraulic means operates only over a very small fraction of an inch (the distance necessary for the clamp to move to compress the paper pile after it has contacted the paper pile) force multiplying hydraulic means

65 may be utilized for this purpose with a relatively very small volume of hydraulic fluid.

It will be obvious that my invention as described above is capable of many variations and modifications. Thus in Figures 6, 7 and 8, I have shown a slight variation of the hydraulic portion of the operating device.

In the case of Figures 6, 7 and 8, the clamp 75 10, the mechanical means therefor and the means

for preventing canting thereof are the same as that shown in Figures 1 to 3 and have thus been given the same reference numbers.

Similarly, the pistons 37 and 44 in the upper hydraulic cylinder 70 operate in the same manner as in the case of Figures 1 to 3 and have also been given the same reference numbers.

Also in Figures 6, 7 and 8, the mechanical drive from crank 56 first causes the link 50 to pivot around pivot 52 and after the downward movement of clamp 10 is mechanically stopped by the paper pile, the link 50 pivots around the upper pivot 33 to operate the hydraulic mechanism to move the pistons 37 and 44 outwardly.

In the case of Figures 6, 7 and 8, the hydraulic system is modified so that the link 159 attached to the lower pivot 52 of link 50 is connected by pivot 160 to piston rod 161 which carries piston 162 rigidly secured thereon.

Valve 165 is slidably mounted on piston rod 161 and is biased to the left by compression spring 167, captured between the surface 168 of valve 165 and surface 169 of piston 162. An additional compression spring 130 is provided, captured between a collar 131 on link 159 and a stationary portion 132 of the frame of the mechanism through an opening 133 of which link 159 passes. Piston 162 operates in the lower cylinder 180 and is connected by duct 183 to the duct 171 which communicates with the upper cylinder 70. The left surface of lower portion of duct 171 is provided with the valve seat 176 in which the surface 175 of valve 165 may be seated to block and seal the duct 171 and thus to break the connection through duct 171 from upper cylinder 70 to lower duct 172 which communicates with the reservoir 73.

The back of cylinder 180 is connected by duct 190 to duct 172 and is thus also in communication with reservoir 73.

The discharge valve 95 blocks the opening around valve seat 96 between the upper cylinder 70 and the duct 103 leading to reservoir 73 and operates in the same manner as the similarly numbered discharge valve of Figures 1, 2 and 3. The operation of this modification of my invention follows exactly the operation of the preferred modification of Figures 1, 2 and 3.

The clamp 10 is first pulled down mechanically by movement to the left of link 54 in response to counterclockwise rotation of the driving crank 56. This first causes the link 50 to pivot counterclockwise on pivot 52 to rotate bell crank lever 24 clockwise to pull down the clamp 10. When the clamp 10 contacts the paper pile, the further rotation of bell crank lever 24 clockwise is blocked.

The pistons 37 and 44 may during this mechanical operation readily move outwardly since the connection including ducts 171 and 172 between cylinder 70 and reservoir 73 is open.

When the downward mechanical movement of clamp 10 is thus blocked by the paper pile, the pivot of link 50 shifts as previously described from the pin 52 to the pin 33 and the link 50 now rotates clockwise around the pivot 33. This pulls the link 159 to the left pulling the piston rod 161 and piston 162 to the left and compressing spring 130. The compression spring 167 between piston 162 and valve 165 drives the valve 165 to the left to seat against the shoulder or valve seat 176 in the duct 171 blocking off the duct 171 as shown in Figure 7 and closing the connection between the cylinder 70 and reservoir 73.

Further movement of link 50 clockwise and link 159 to the left pulling the piston rod 161 to the left now causes compression of spring 167 as well

as further compression of spring 130 and pulls the piston 162 to the left in the lower cylinder 180. The lower cylinder 180, duct 183, the upper portion of duct 171 and cylinder 70 are now a closed hydraulic system.

The relative smallness of the diameter of piston 162 with respect to the diameter of pistons 37 and 44 now produces a force multiplying effect.

As piston 162 is thus pulled further to the left, the fluid is compressed in ducts 183 and 171 and in cylinder 70 forcing the pistons 37 and 44 outwardly under force multiplying pressure. This provides force multiplying hydraulic means for squeezing the clamp down with increased pressure on the paper pile as previously described.

In the event that the movement of piston 162 too far to the left raises the pressure in cylinder 70 beyond the safety limit, the excess liquid may bleed off through the discharge valve 95 as previously described. After the crank 56 has reached the position shown in Figure 8, further rotation will permit the piston rod 161 and link 159 to move to the right under the influence of compression spring 130. The discharge valve 95 will close, if it has already been opened, and a volume of fluid will be confined in the cylinder 70, the upper portion of duct 171, duct 183 and cylinder 180. Consequently, as the piston 162 now moves to the right the pistons 37 and 44 will move inwardly releasing the hydraulic pressure on the clamp because the volume of cylinder 180 will increase owing to the motion to the right of the pressure piston 162.

Thus the hydraulic pressure will be quickly released during the return stroke of crank 56.

On completion of the movement to the right of piston 162, the valve 165 moves to the right and opens the duct 171 establishing communication from cylinder 70 through ducts 171 and 172 to the reservoir 73.

The completion of the counterclockwise rotation of the crank 56 back to the position of Figure 6 will now cause the link 50 to pivot clockwise around pivot 52 rotating bell crank lever 24 counterclockwise and lifting the clamp 10.

In this modified form also it will be seen that the clamp 10 is moved downwardly to contact the upper surface of the paper pile with a rapid mechanical movement of relatively low power and is then squeezed down the remaining fraction of an inch necessary to compress the paper pile by force multiplying hydraulic means.

My invention thus reduces the amount of power required. The mechanical force required to move the clamp down need be only slightly greater than that necessary to overcome the counter-balancing means to maintain the clamp in raised position.

When the clamp contacts the pile, the drive means is then effective to squeeze the clamp down hard on the paper pile to compress the same with several tons of pressure owing to the fact that when the paper pile is contacted, force multiplying hydraulic means is introduced between the drive and the pull bar of the clamp.

It is no longer necessary to develop the full clamping pressure in the driving mechanism and the use of such force multiplying hydraulic means makes it possible to incorporate much less powerful and expensive driving means in the machine since the hydraulic force multiplying means is utilized only over a fraction of an inch of the entire stroke of the clamp (which stroke may be as much as 6").

The hydraulic mechanism itself requires relatively small quantities of fluid and is simple in

construction. This is so because long ducts and long strokes or long angles of movement of the driving means become unnecessary. Even with a high pile of relatively soft and pulpy paper the amount of movement required for the clamp to compress the paper pile after the clamp has first contacted the paper pile may be of the order of $\frac{1}{2}$ " and less.

The developed pressure in the cylinder 10 is proportional to the area of the pistons 37 and 44 and the pressure piston 62. For example, if the pistons 37 and 44 are 6 inches in diameter and the pressure piston 62 and the piston rod 61 are respectively 3" and 1" in diameter, then the combined pressure on the bell cranks 24 and 26 is 9 times greater than the pressure exerted on the liquid by piston 62.

By means of the foregoing, therefore, I have provided a novel hydraulic operating means for the clamp of a paper cutter wherein the clamp is brought down mechanically in any suitable manner into engagement with the upper surface of the paper stack and after it has contacted the upper surface of the paper stack is then forced down by force multiplying hydraulic means to compress the stack with great pressure.

In the foregoing, I have described my invention solely in connection with illustrative embodiments thereof. Since many variations and modifications of my invention will now be obvious to those skilled in the art, I prefer to be bound not by the specific disclosures herein contained but only by the appended claims.

I claim:

1. In combination, a clamp for operating on material, a support for said material, a source of driving power, a first drive connecting from said source of power to said clamp, a second drive connection from said source of power to said clamp, means whereby said second connection is ineffective while said first connection transfers driving power from said source to operate said clamp, and means whereby after said first drive connection has effected a predetermined operation on said clamp, said second drive connection becomes effective to transfer driving power from said source to further operate said clamp.

2. In combination, a clamp for operating on material, a support for said material, a source of driving power, a first drive connecting from said source of power to said clamp, a second drive connection from said source of power to said clamp, means whereby said second connection is ineffective while said first connection transfers driving power from said source to operate said clamp, and means whereby after said first drive connection has effected a predetermined operation on said clamp, said second drive connection becomes effective to transfer driving power from said source to further operate said clamp, the force multiplication of said second drive connection being greater than said first drive connection.

3. In combination, a clamp for operating on material, a support for said material, a source of driving power, means for connecting said source to said clamp for operating said clamp to compress said material, and additional connections between the source of power and the clamp for increasing the force multiplication of said connecting means to increase the force applied to said material from said source, said additional connections being operative in response to the engagement of the clamp with the material.

4. In combination, an operating member for clamping material, a support for said material, a source of driving power, means for connecting said source to said operating member for applying clamping force on said material, and additional connections between the source of power and the clamp for increasing the force multiplication of said connecting means to increase the force applied to said material from said source; said additional connections being operative in response to the engagement of the clamp with the material and in proportion to the resistance encountered by the clamp in engaging the material.

15 5. A clamp for compressing a paper stack; a support for said paper stack; said clamp being movable toward and away from said paper stack; drive means; a first set of connections from said drive means to said clamp operable to move said clamp into contact with said paper stack; and additional force multiplying connections between said drive means and said clamp for forcing said clamp into high pressure engagement with said paper stack.

20 6. A clamp for comprising a paper stack; a support for said paper stack; said clamp being movable toward and away from said paper stack; drive means; a first set of connections from said drive means to said clamp operable to move said clamp into contact with said paper stack; and additional force multiplying connections between said drive means and said clamp for forcing said clamp into high pressure engagement with said paper stack after said clamp has come into engagement with said paper stack.

25 7. A clamp for compressing a paper stack; a support for said paper stack; said clamp being movable toward and away from said paper stack; drive means; a first set of connections from said drive means to said clamp operable to move said clamp relatively rapidly into contact with said paper stack; and additional force multiplying connections between said drive means and said clamp for forcing said clamp into high pressure engagement with said paper stack.

30 8. A clamp for compressing a paper stack; a support for said paper stack; said clamp being movable toward and away from said paper stack; drive means; a first set of connections from said drive means to said clamp operable to move said clamp relatively rapidly into contact with said paper stack; and additional force multiplying connections between said drive means and said clamp for forcing said clamp into high pressure engagement with said paper stack after said clamp has come into engagement with said paper stack.

35 9. A clamp for compressing a paper stack; a support for said paper stack; said clamp being movable toward and away from said paper stack; drive means; a first set of connections from said drive means to said clamp operable to move said clamp into contact with said paper stack; and additional force multiplying hydraulic connections between said drive means and said clamp for forcing said clamp into high pressure engagement with said paper stack; said additional connections being operative in response to the engagement of the clamp with the material and in proportion to the resistance encountered by the clamp in engaging the material.

40 10. A clamp for compressing a paper stack; a support for said paper stack; said clamp being movable toward and away from said paper stack; drive means; a first set of connections from said

drive means to said clamp operable to move said clamp relatively rapidly into contact with said paper stack; and additional force multiplying relatively short stroke hydraulic connections between said drive means and said clamp for forcing said clamp into high pressure engagement with said paper stack.

11. A clamp for compressing a paper stack; a support for said paper stack; said clamp being movable toward and away from said paper stack; drive means; a first set of connections from said drive means to said clamp operable to move said clamp relatively rapidly into contact with said paper stack; and additional force multiplying relatively short stroke hydraulic connections between said drive means and said clamp for forcing said clamp into high pressure engagement with said paper stack after said clamp has come into engagement with said paper stack.

12. A clamp for compressing a paper stack; a support for said paper stack; said clamp being movable toward and away from said paper stack; drive means; a first set of connections from said drive means to said clamp operable to move said clamp relatively rapidly into contact with said paper stack; and additional force multiplying relatively short stroke hydraulic connections between said drive means and said clamp for forcing said clamp into high pressure engagement with said paper stack after said clamp has come into engagement with said paper stack; said force multiplying hydraulic connection being brought into operation by the engagement of the clamp with the paper stack.

13. In a paper cutting machine a table for supporting a paper stack to be cut; a clamp for compressing the paper stack; said clamp being movable toward and away from said paper stack; drive means for said clamp; a connecting link, one end of said link being connected to said clamp; a pivotally mounted lever; the first end of said lever being connected to the other end of said link; the second end of said lever being connected to said drive means; operation of said drive means being effective to rotate said lever to bring the clamp into contact with said paper stack; force multiplying operating means also connected to said second end of said lever; said force multiplying operating means being automatically connected between said drive means and said lever when the clamp engages the paper stack.

14. In a paper cutting machine a table for supporting a paper stack to be cut; a clamp for compressing the paper stack; said clamp being movable toward and away from said paper stack; drive means for said clamp; said clamp having a pull bar; a pivotally mounted lever; the first end of said lever being connected to said pull bar; a link pivotally connected at one end to the second end of said lever; force multiplying connecting means; the opposite end of said link being connected to the driving side of said force multiplying connecting means; the driven side of said force multiplying connecting means being connected to the second end of said lever; said drive means being connected to said link between the ends thereof; said operating means moving said link about the pivot on its said opposite end to rotate said lever and move the clamp into engagement with the paper stack; said drive means thereafter moving the opposite end of said link about the pivot at its first mentioned end to actuate said force multiplying hydraulic means to move said clamp into pressure engagement with said paper stack.

move said clamp into pressure engagement with said paper stack.

15. In a paper cutting machine a table for supporting a paper stack to be cut; a clamp for compressing the paper stack; said clamp being movable toward and away from said paper stack; drive means for said clamp; said clamp having a pull bar; a pivotally mounted lever; the first end of said lever being connected to said pull bar; a link pivotally connected at one end to the second end of said lever; force multiplying hydraulic connecting means; the opposite end of said link being connected to the driving side of said force multiplying hydraulic connecting means; the driven side of said force multiplying hydraulic connecting means being connected to the second end of said lever; said drive means being connected to said link between the ends thereof; said operating means moving said link about the pivot on its said opposite end to rotate said lever and move the clamp into engagement with the paper stack; said drive means thereafter moving the opposite end of said link about the pivot at its first mentioned end to actuate said force multiplying hydraulic means to move said clamp into pressure engagement with said paper stack.

16. In a paper cutting machine a table for supporting a paper stack to be cut; a clamp for compressing the paper stack; said clamp being movable toward and away from said paper stack; drive means for said clamp; said clamp having a pull bar; a pivotally mounted lever; the first end of said lever being connected to said pull bar; a link pivotally connected at one end to the second end of said lever; force multiplying hydraulic connecting means having a driving piston of relatively small diameter and a driven piston of relatively large diameter; the opposite end of said link being connected to the driving piston of said force multiplying hydraulic connecting means; the driven piston of said force multiplying hydraulic connecting means being connected to the second end of said lever; said drive means being connected to said link between the ends thereof; said drive means moving said link about the pivot on its said opposite end to rotate said lever and move the clamp into engagement with the paper stack; said drive means thereafter moving the opposite end of said link about the pivot at its first mentioned end to actuate said force multiplying hydraulic means to move said clamp into pressure engagement with said paper stack.

17. In a paper cutting machine a table for supporting a paper stack to be cut; a clamp for compressing the paper stack; said clamp being movable toward and away from said paper stack; drive means for said clamp; said clamp having a pull bar; a pivotally mounted lever; the first end of said lever being connected to said pull bar; a link pivotally connected at one end to the second end of said lever; force multiplying hydraulic connecting means having a driving piston of relatively small diameter and a driven piston of relatively large diameter; the opposite end of said link being connected to the driving piston of said force multiplying hydraulic connecting means; the driven piston of said force multiplying hydraulic connecting means being connected to the second end of said lever; said drive means being connected to said link between the ends thereof; said drive means moving said link about the pivot on its said opposite end to rotate said lever and move the clamp into engagement with the paper stack; said drive means thereafter moving the opposite end of said link about the pivot at its first mentioned end to actuate said force multiplying hydraulic means to move said clamp into pressure engagement with said paper stack.

posite end to rotate said lever and move the clamp into engagement with the paper stack; said drive means thereafter moving the opposite end of said link about the pivot at its first mentioned end to actuate said force multiplying hydraulic means to move said clamp into pressure engagement with said paper stack; a cylinder for said driving piston; a cylinder for said driven piston; a connecting duct between said cylinders; a reservoir and a by-pass duct between said cylinders and said reservoir; means for closing said by-pass duct as said driving cylinder is moved in the driving direction.

18. In a paper cutting machine a table for supporting a paper stack to be cut; a clamp for compressing the paper stack; said clamp being movable toward and away from said paper stack; drive means for said clamp; said clamp having a pull bar; a pivotally mounted lever; the first end of said lever being connected to said pull bar; a link pivotally connected at one end to the second end of said lever; force multiplying hydraulic connecting means having a driving piston of relatively small diameter and a driven piston of relatively large diameter; the opposite end of said link being connected to the driving piston of said force multiplying hydraulic connecting means; the driven piston of said force multiplying hydraulic connecting means being connected to the second end of said lever; said drive means being connected to said link between the ends thereof; said drive means moving said link about the pivot on its said opposite end to rotate said lever and move the clamp into engagement with the paper stack; said drive means thereafter moving the opposite end of said link about the pivot at its first mentioned end to actuate said force multiplying hydraulic means to move said clamp into pressure engagement with said paper stack; a cylinder for said driving piston; a cylinder for said driven piston; a connecting duct between said cylinders; a reservoir and a by-pass duct connecting said cylinders and said reservoir; means for closing said by-pass duct as said driving cylinder is moved in the driving direction; an additional duct between the cylinder housing the driven piston and the reservoir; valve means between said cylinder and said additional duct controlling the maximum pressure in said cylinder.

19. In a paper cutting machine a table for supporting a paper stack to be cut; a clamp for compressing the paper stack; said clamp being movable toward and away from said paper stack; drive means for said clamp; said clamp having a pull bar; a pivotally mounted lever; the first end of said lever being connected to said pull bar; a link pivotally connected at one end to the second end of said lever; force multiplying hydraulic connecting means having a driving piston of relatively small diameter and a driven piston of relatively large diameter; the opposite end of said link being connected to the driving piston of said force multiplying hydraulic connecting means; the driven piston of said force multiplying hydraulic connecting means being connected to the second end of said lever; said drive means being connected to said link between the ends thereof; said drive means moving said link about the pivot on its said opposite end to rotate said lever and move the clamp into engagement with the paper stock; said drive means thereafter moving the opposite end of said link about the pivot at its first mentioned end to actuate said force multiplying hydraulic means to move said clamp into

pressure engagement with said paper stack; a cylinder for said driving piston; a cylinder for said driven piston; a connecting duct between said cylinders; a reservoir and a by-pass duct between said cylinders and said reservoir; a valve for closing said by-pass duct; said valve being operable to closed position on movement of said driving piston in the driving direction and being operable to open position on return movement of said driving piston.

20. A clamp for compressing a paper stack; said clamp being movable toward and away from said paper stack; drive means; a first set of connections from said drive means to said clamp operable to move said clamp into contact with said paper stack; and additional force multiplying connections between said drive means and said clamp for forcing said clamp into high pressure engagement with said paper stack; and means for controlling the clamp during its movement toward and away from said paper stack to avoid tilting of said clamp.

21. A clamp for compressing a paper stack; said clamp being movable toward and away from said paper stack; drive means; a first set of connections from said drive means to said clamp operable to move said clamp into contact with said paper stack; and means for controlling the clamp during its movement toward and away from said paper stack to avoid tilting of said clamp; said means comprising a rotatable shaft parallel to said clamp; and a gear connection from opposite ends of said shaft to opposite ends of said clamp.

22. A clamp for compressing a paper stack; said clamp being movable toward and away from said paper stack; drive means; a first set of connections from said drive means to said clamp operable to move said clamp into contact with said paper stack; and means for controlling the clamp during its movement toward and away from said paper stack to avoid tilting of said clamp; said means comprising a rotatable shaft parallel to said clamp; a gear at each end of said shaft; a rack at each end of said clamp engaged by said gear, the torsional resistance of said shaft resisting uneven movement of the opposite ends of the clamp.

23. A clamp for compressing a paper stack; said clamp being movable toward and away from said paper stack; drive means; a first set of connections from said drive means to said clamp operable to move said clamp relatively rapidly into contact with said paper stack; and additional force multiplying connections between said drive means and said clamp for forcing said clamp into high pressure engagement with said paper stack after said clamp has come into engagement with said paper stack; said first set of connections being connected to one side of said clamp; said additional force multiplying connections being connected to both sides of said clamp.

FREDERICK W. SEYBOLD.
